[57] CLAIM

I claim the ornamental design for a wheel, as shown and described.

DESCRIPTION

FIG. 1 is a front elevational view of a wheel showing my new design;

FIG. 2 is an enlarged partial view shown from the upper right corner thereof;

FIG. 3 is a perspective view thereof;

FIG. 4 is an enlarged partial perspective view of the upper left corner thereof; and,

FIG. 5 is a side elevational view thereof, with the opposite sides being a mirror image.
